BAG FORMING AND FILLING MACHINE

Theodore Schilder, New York, N. Y., assignor to
Fred Goat Co., Inc., New York, N. Y., a corpora-
tion of New York

Application April 11, 1933, Serial No. 665,530

26 Claims. (Cl. 93—3)

This invention relates to a bag forming and filling machine, and more particularly to a high-speed turret machine for forming bags of the Anderson type.

5 A known form of machine for forming and simultaneously filling paper bags is the Anderson type of machine disclosed in Anderson Patent 1,151,233, issued August 24, 1915. The said machine is generically characterized by a hollow 10 plunger which is rectangular in cross-section and vertically reciprocable through a die on which a blank of paper is preliminarily placed. As the plunger descends through the die, the paper is folded and wrapped around the open lower end 15 of the plunger to form a rectangular bag which is filled by discharging the filling material, which ordinarily is granular or powdery, downwardly through the plunger into the embryo bag. The plunger is then elevated and the filled bag is 20 moved onwardly to a bag closing station where the open top of the bag is folded and appropriately treated to seal the same.

The speed of the machine is obviously limited by the total of the time increments needed for the 25 various successive operations, such as, the feeding of paper to the die, the descent of the plunger to form the bag, the measuring and feeding of a charge of material to the plunger as well as the discharge of the material into the bag, the elevation of the plunger, and the delivery of the 30 formed and filled bag from the die. The primary object of the present invention is to generally improve machines of the Anderson type, with the particular object in view of greatly speeding up 35 the operation of the machine without, however, shortening the time available for each bag forming operation, and, in fact, actually increasing the same, if desired. This object I fulfil by the provision of a rotatable turret on which there are 40 distributed a plurality of bag forming and filling stations, each of the stations including a die and a hollow plunger reciprocable therethrough in the conventional manner. With this arrangement, ample time is provided for the forming and filling 45 of each bag, for nearly all of the time of rotation of the turret may be used for operation upon a single bag at a single station, while the output of the machine as a whole is obviously increased due to the substantial number of stations 50 operating. At the same time, the machine is compact and requires no more space and supervision than the old form of Anderson machine having only a single operating station.

55 Further objects of the present invention center about the feed of the filling material or powder

to the bags and are: to make possible a continuous and self-regulating supply of powder to the machine through a simple stationary pipe, the distribution of the powder around the several stations through the use of an annular hopper located above the stations and rotating therewith, as well as the continual and automatic agitation and leveling of the powder in the hopper; the provision of means for measuring the individual charges of powder in an accurate manner, together with micrometric means for accurately adjusting this measurement to a desired value; and the provision of a retaining valve and operating linkage therefor so disposed within the plunger and so operated as to be fully openable 10 and to present a clear hollow plunger for direct straight flow of the powder downwardly through the plunger into the bag.

A further object of the present invention centers about the paper feeding means and is to design paper feeding mechanism which is adapted to remain stationary alongside of the rotating turret; which feeds blanks of paper to the turret in proper position thereon without necessitating any dwell or interruption of the rotation of the 25 turret; which is capable of severing and feeding blanks of desired and uniform dimension from a continuous web or roll of paper; which includes means for unrolling a slack section of paper from the roll, and yet which is yieldably arranged to 30 obviate the possibility of tearing the web of paper, particularly when the roll is new and heavy; which further includes roller feed means to advance the paper toward the turret and upon a stationary support means or skeleton table above 35 the dies, together with additional feed fingers for advancing the already severed blank of paper to exact desired position above the die; and, finally, which further employs holding fingers on the turret together with appropriate operating and 40 trip mechanism for dropping these fingers upon the blank as the die passes the paper feeding station in order to hold the blank in position on the die and to carry it with the revolving die.

45 Further objects of the present invention center about the construction of the turret of the machine and its relation to the frame of the machine, and include simplification of the mechanism needed for providing the many complex and properly timed operations of the bag forming 50 and filling stations, which is accomplished, in a general way, by associating with the rotating turret a series of stationary cams cooperating with cam followers on the turret, so that the physical rotation of the turret is itself used to 55

cause and to properly time the various necessary movements and operations. Other objects of the present invention center about the delivery mechanism, and include: the provision of a simple and effective form of delivery conveyor leading away from the machine; the provision of means for transferring the formed and filled bags from the turret to the conveyor; and the proper interrelation and synchronization of the turret, the conveyor, and the delivery wheel therebetween. Still further objects of my invention concern the drive of the machine, including its operation from a single power source, appropriate control or clutch mechanism, preferably embodying safety clutch or over-load clutch means, and the disposition of the numerous operating cams for many of the machine movements upon a single cam shaft, thereby facilitating timing of the machine.

To the accomplishment of the foregoing and such other objects as will hereinafter appear, my invention consists in the bag forming and filling machine and the elements thereof and their relation one to the other, as hereinafter are more particularly described in the specification and sought to be defined in the claims. The specification is accompanied by drawings, in which:

Fig. 1 is a partially sectioned front elevation of a machine constructed in accordance with the present invention;

Fig. 2 is a partially sectioned plan view thereof;

Fig. 3 is an enlarged section explanatory of the paper unrolling arm;

Fig. 4 is a vertical section taken through one of the bag forming and filling stations on the turret;

Fig. 5 is a section through the plunger, taken in the plane of the line 5—5 in Fig. 4;

Fig. 6 is a horizontal section taken in the plane of the line 6—6 in Fig. 4;

Fig. 7 is a plan view of the paper feed mechanism, taken approximately in the plane of the line 7—7 of Fig. 1;

Fig. 8 is a detail of the feed fingers and is taken in the plane of the line 8—8 of Fig. 7;

Fig. 9 is a detail of the drive mechanism for the paper feed roller, and is taken in the plane of the line 9—9 of Fig. 7;

Fig. 10 is a section through the paper feed and cutting mechanism, and is taken in the plane of the line 10—10 of Fig. 7;

Fig. 11 is a detail explanatory of the delivery system, and is taken in the plane of the line 11—11 of Fig. 2; and

Fig. 12 is a detail explanatory of the cam shaft drive and safety clutch.

Referring to the drawings, the present machine comprises a turret T carrying a plurality of bag forming and filling stations S and rotatable on a stationary frame F. Each of the bag forming stations includes a hollow rectangular plunger P reciprocable through a die D. Paper is fed from a roll R through appropriate paper feeding mechanism M to a point over the dies D, the continuous webs being severed into blanks of desired dimension by a knife K. As plunger P descends through the die D, the paper is folded and wrapped about the end of the plunger to form rectangular open-topped bags B. The bags are filled through the plunger P with granular or powdery filling material, a constant supply of the material being carried in the rotatable annular hopper H from which the material is fed downwardly to valve chambers V located above each of the plungers or bag forming stations. Individual charges of predetermined amount are

measured out in the valve chambers V and dropped downwardly into the plunger P. The formed and filled bags are delivered to a delivery conveyor C from the turret T by an appropriate transfer or delivery wheel W.

The general arrangement of the machine having been referred to, the various parts thereof will next be described in greater detail, and, for convenience, the description will be divided into sections taking up the powder feed mechanism, the paper feed mechanism, the turret, the delivery system, and the drive mechanism, after which the operation of the machine will be summarized.

Powder feed mechanism

5

15

The powder feed mechanism is best shown in Figs. 1, 2, 4, 5, and 6, referring to which, a supply of the filling material, which may be granular or flaky as well as powdery but which, for convenience, will be referred to as powder, is supplied through a simple stationary pipe 12 anchored in one corner of the triangular top plate 14 of the frame of the machine, the lower end of pipe 12 terminating within the hopper H. This hopper is annular and forms the uppermost portion of turret T, the hopper extending around and, in effect, interconnecting the stations S which, in the present machine, are four in number. The hopper is preferably downwardly tapering, as is clearly evident from an inspection of Figs. 1 and 4 showing the converging side walls 16 and 18. The rotating hopper is continually supplied with powder from pipe 12 as fast as the powder is filled into the bags, the powder in the hopper being maintained at a constant desired level by the immersion of delivery pipe 12 in the hopper together with the continuous rotation of the hopper relative to the stationary pipe.

The powder being filled into the bags may, in some cases, for example gelatine powder intended for household use as a dessert, have a tendency to stick to the walls of the hopper or to form lumps; and, to obviate this difficulty, the hopper is preferably provided with means to constantly agitate the powder therein. For this purpose the triangular top plate 14 of the frame is preferably provided with several combs 20, best shown in Figs. 1 and 2, the teeth of which are graduated in length to fit the tapered shape of the hopper, and which serve to constantly agitate the powder. If desired, more than two combs may be used, and the teeth may be staggered relative to one another. It should also be noted that the combs slope in the direction of rotation of the turret, which is clockwise as viewed in plan, so that they have a tendency to force the powder downwardly into the valve chambers V, these valve chambers being located immediately beneath the hopper and communicating therewith through appropriate passages 22, as is best shown in Fig. 4. There are four valve chambers V distributed in quadrature around the turret and beneath the hopper and corresponding to the four bag forming and filling stations S. Referring to Fig. 4, the valve chamber is provided with a measuring box 24 the top of which may be closed by a cut-off valve 26, and the bottom of which may be opened by a valve 52, thus dropping a measured charge of powder into the open upper end of plunger P, where it may be temporarily retained by a plunger valve 110 until the plunger descends to form the bag. The cut-off valve 26 is preferably of the sliding type shown, mounted on a valve arm 28 operable by a valve rod 30

which projects out of the valve chamber and carries an arm 32 connected through a link 34 to an arm 36 which in turn moves a sidewardly displaced arm 38 connected by an outwardly projecting cam follower rod 40 slidable in boss 41 to a cam follower wheel 42. This in turn rides upon the surface of an annular cam 44 mounted on a ring 46 extending entirely around the turret and mounted upon the three upright pillars 48 of the machine frame, as is best shown in Fig. 1. As the turret revolves, the cam follower 42 is operated by cam 44 to open or close the cut-off valve 26. It may be remarked that the inwardly and then outwardly directed linkage 34 and 40 is introduced to displace the cam follower mechanism sidewardly of the valve chamber, and to reduce the diametrical dimension of the turret and surrounding cam.

The bottom valve 50 is mounted on a valve rod 52 connected outside of the valve chamber to an operating arm 54 in turn operated by a relatively long operating arm 56 oscillated, through linkage 58, lever 60, cam follower rod 62 slidable in boss 63, and cam follower 64, by an annular cam 66 carried within a ring 68 itself mounted on the three pillars 48 of the frame. Levers 54 and 56 are employed to step up the angular oscillation of the valve, so that valve 50 may be dropped downwardly to a substantially vertical and fully opened position without, however, necessitating an inconvenient cam elevation or inward projection of the cam projections 66 carried by the ring 68. The measured charge of powder from the measuring box 24 is dropped downwardly out of the valve chamber V through an appropriate discharge opening 70 into the open upper end of plunger P, which at that time is in the elevated position shown in Fig. 4, the upper end of the plunger then bearing against a preferably rubber bumper 72 located at the bottom of the plate 74. Valve chamber V is secured on the periphery of a casting forming the upper part of the rotatable turret T, this casting including the lower plate 74 and an upper plate 76, between which the valve chamber is secured, as well as interconnecting webs 78 and 80 which space the plates 74 and 76 apart and provide supports and guides for the valve linkage already referred to. (The bosses 41 and 63 correspond to bosses 41 and 63, but belong to the next station on the turret.)

The volume of the charge measured out by the measuring box 24 is adjustable, and this adjustment is in the present case obtained by the use of a movable side 82 the upper end of which is fixed and the lower end of which may be oscillated by a micrometric control screw 84 having a dial 86 secured to the outer end thereof, the said dial cooperating with an appropriate fixed scale 88. The adjustment may be locked by an internally threaded handle 90 acting as a lock nut which jams against the valve chamber.

The plunger P is a substantially straight hollow tube which is rectangular in cross-section, being made, for example, of cold rolled steel. The tube is clamped near its upper end in a plunger casting 92 (see Fig. 6), the inner portion of which is provided with tongues or runners 94 reciprocable in channels or tracks 96 formed on the outer surface of a casting 98 forming a part of the rotatable turret. The plunger casting 92 may be tightly clamped on the upper end of the plunger through a separable outer portion 100 which in turn carries a cam follower wheel 102. The plunger casting 92 may itself be applied to

or removed from the turret casting 98 by removing the guide rails 104. The plunger is reciprocated vertically through the cooperation of cam follower 102 with a cam groove formed between the upper and lower sections of a cylindrical cam 106, this cam, like the rings 46 and 68 already referred to, being secured to the pillars 48 of the frame (see Fig. 1).

To retain the charge of powder in the plunger temporarily until the bag is formed, the plunger 10 is provided near its lower end with a plunger valve 110 operated through a valve rod 112 carrying an arm 114 connected through an upwardly extending link 116 to an arm 118 controlled from without the plunger by an outwardly projecting rod 120 carrying a cam follower arm 122 bearing at its end a cam follower roller 124. It should be noted in Fig. 4 that the valve 110, even in its closed position, is sloped downwardly, making it readily possible to fully open the valve by a relatively small downward oscillation. It should also be noticed, as by reference to Fig. 5 that the complete control mechanism, including the arms 114 and 118 with interconnecting link 116, are disposed close to the outer wall of the plunger. They are preferably concealed by a dummy wall 126 extending parallel and close to the edge wall of the plunger and having its upper and lower ends bent outwardly to join the walls of the plunger, as is shown in Fig. 5. It may be remarked that, in order to show the mechanism involved, the inward displacement of wall 126 is exaggerated in Fig. 5, and in actual practice this displacement may be and preferably is minimized. This construction, together with the full opening of the plunger valve 110, gives to the plunger a substantially clear hollow construction permitting a direct straight downward flow of the powder through the plunger and into the bag. This in turn obviates difficulties due to sticking or lumping of the powder on the walls and valve mechanism of the plunger, as results when the powder is caused to take a more circuitous or indirect path for delivery.

The cam follower 124 rides along a vertical cam surface 125, best shown in Fig. 1, this cam being essentially a rib cast integrally with the turret casting 98. Near the end of the downward stroke of the plunger, the cam surface rises and trips the valve to its fully opened position. Considering all of the powder valves, the cut-off valve 28 is never opened except when the bottom valve 50 is closed, and the bottom valve 50 is never opened except when the cut-off valve 28 is closed. The bottom valve 50 is opened when the plunger is in its elevated position, and at this time the retaining valve 110 is, of course, closed. It will be appreciated, of course, that the plunger valve is preferably located near the bottom of the plunger to permit instantaneous delivery into the bag, and that the internal valve operating linkage mechanism is then necessitated because the outer surface of the entire lower part of the plunger is left unobstructed for reciprocation through the die.

Paper feed mechanism

As is best shown in Figs. 1 and 2, the paper is fed from a roll R supported in conventional fashion upon appropriate arms 130 projecting outwardly from the base 132 of the frame F. The web of paper is first passed downwardly around a roller 134 at the outer end of a paper unrolling arm 136, this arm being best shown in Fig. 3. The web then moves upwardly through a friction device 138 to the feed mechanism M. Referring

to Fig. 3, the friction device 138 comprises a pair of rods 140 and 142 so displaced with respect to one another as to cause reverse bending of the web of paper. This applies friction to the paper, 5 which restrains the web from moving downwardly when the paper unrolling arm 136 descends, thus insuring that the paper will be unrolled from the roll R to provide the desired slack in the web.

The paper unrolling arm 136 is pivoted on a 10 fixed bearing 144 and carries intermediate its length a cam follower 146 riding in the cam groove 148 of a cam 5. To overcome any tendency for the paper rolling arm to tear the web, particularly when the paper roll is a freshly started and relatively heavy one, the arm 136 may be made yieldable to give under the initial strain of its downward movement. For this purpose, the arm is divided and provided with an outer portion 150 pivoted at 152 to the inner portion 154. The inner 15 portion is extended outwardly to form a non-yieldable extension 156 between which and the outer portion 150 there is interposed a compression spring 158 held in place and adjustable through a tensioning bolt 160. Inasmuch as the 20 yieldability of the arm is intended merely to absorb the shock of initial movement so as to set the paper roll into movement gradually, and is not intended to materially reduce the amount of slack provided in the web of paper, the yieldability 25 of the arm may be limited by a positive stop 162 bearing against an abutment 164, the permitted movement being adjustable by altering the position of stop 162.

The web of paper then passes between a lower 30 feed roller 170 and an upper pressure wheel 172, as is best shown in Fig. 10. Feed roller 170 is mounted on a shaft 174 which is intermittently and uni-directionally rotated by mechanism next described. Referring to Figs. 7 and 9, there is a 35 generally upright and vertically reciprocable rack bar 176 meshing with a pinion 178 secured to the outer or driving portion 180 of a friction or roller clutch the inner or driven portion 182 of which is in turn keyed to a shaft 183 and gear 184. It 40 will be understood that the spring operated rollers 186 between the driving and driven portions of the clutch cause the clutch to rotate gear 184 in the direction of the arrow but permit slippage in the reverse direction. Gear 184 meshes with pinion 186 which in turn is keyed to the shaft 174 45 of the paper feed roller 170 already referred to. It will thus be seen that the feed roller is adapted to intermittently advance the web of paper toward the turret. Return movement of the feed roller is prevented by a holding pawl in the form of an eccentric friction brake, omitted in Fig. 9, but shown in Figs. 1 and 7. Referring to these 50 figures, the eccentric friction brake comprises a wheel 188 having a grooved periphery cooperating 55 with the wedge-shaped end of a brake arm 190, the wedge-shaped end being arcuate about a center eccentric with respect to the center of oscillation of the arm 190, so that movement of the shaft 183 of the gear 184 is freely permitted 60 in a counter-clockwise direction, as viewed in Figs. 1 and 9, but is effectually prevented in a clockwise direction.

The paper fed by rolls 170 and 172 is delivered 65 upon a support in the form of a skeleton table 192 comprising, in the present instance, only an edge adjacent the feed rollers and a trailing edge 194, as is best shown in Fig. 7. The skeleton table 192 is located immediately above the die carrying plate 196 of the turret and therefore immediately 70 above the upper surfaces or die plates of the bag 75

forming dies D. The skeleton table is mounted upon the inner face of pedestal 198 which supports the paper feeding rolls and the knife K.

When a measured blank of paper has been fed 5 past the knife and is supported upon the skeleton table, the blank is severed by the cutting mechanism K. This comprises a knife blade 200 pivoted at 202 on a knife supporting arm 204. The opposite or free end 206 of the knife blade is reciprocated through a generally upright link 10 208, best shown in Fig. 1. This link is in turn pivoted at the upper end of a rod 210 vertically reciprocable in a bushing 212 mounted on the machine frame. Rod 210 is a cam follower rod the lower end of which is provided with a cam 15 follower wheel 214 running in a cam groove in the face of a cam 4, best shown in Fig. 2. The mounting of the cam follower 214 is preferably further provided with sidewardly projecting vanes or wings 216 (see Fig. 1) which bear against the 20 side face of cam 4 and prevent rotation of the cam follower rod, thereby holding the cam follower with its axis in desired alignment.

Just before the cutting mechanism severs the blank from the web, the blank is preferably 25 seized to prevent movement during and after the cutting operation. For this purpose, the paper feed mechanism includes a pair of feed fingers 220, best shown in Figs. 7 and 8. These feed fingers are reciprocable toward and from the 30 turret, and, to accommodate this movement, the trailing edge 194 of the skeleton table is preferably cut away or recessed, as is indicated at 222 in Fig. 7. The lower finger 220 is secured to the lower half 224 of a split rod reciprocable in a 35 sleeve 226 forming a part of the pedestal supporting the paper feed mechanism. The upper finger is oscillatable with a partial pinion 228 meshing with a rack 230 formed at the inner end of the upper portion 232 of the split rod received 40 in the sleeve 226. The fingers 220 are operated by a generally upright lever arm 234 the forked upper end of which bears against a pin 236 secured to rod 232. It will be evident from an inspection of Fig. 8 that clockwise movement of 45 lever 234 first causes closing of the feed fingers 220 upon the blank of paper (this blank being numbered 238 in Fig. 7), and thereafter causes bodily movement inwardly of the feed fingers with the blank of paper to position the blank symmetrically directly over the die plate and directly beneath the plunger. 50

While not strictly a part of the generally stationary paper feeding mechanism, the delivery of the blanks of paper is further accomplished with the aid of pairs of holding fingers 240 mounted on and rotatable with the turret, these fingers being most clearly shown in Fig. 7. These fingers are normally elevated, but, as the die passes the paper feeding mechanism, and, specifically, just 55 when these come into registry or indexing relation, the holding fingers 240 are dropped upon the blank of paper and the feed fingers 220 are released, so that the blank is held in proper position on the die and is carried around with the die and the turret. For this purpose, the fingers are normally urged downwardly by springs 242 but are normally held upwardly against the spring pressure by a trigger 244. The lower end 60 of the trigger lever is connected, by means of a trigger rod 246, to a trip finger 248. As is best shown in Figs. 7 and 10, the pedestal 198 of the paper feed mechanism is provided with a knock-out cam 250 against which the trip finger 248 65

bears as the die revolves past the paper feeding mechanism. The cam 250 pushes the trip rod 246 inwardly, thereby releasing trigger 244 and permitting the holding fingers 240 to drop smartly upon the blank of paper. The extremities of fingers 240 are preferably provided with generally hemispherical rubber bumpers 252.

The holding fingers 240 are again elevated by push rods 254 (see Fig. 1) connected at the upper ends of cam follower rods 256 the lower ends of which carry cam follower wheels 258 which ride upon the upper surface of the frame plate 260. At appropriate points, the frame plate is provided with cam lift elements 262 which elevate the holding fingers, whereupon they are held in elevated position by the trigger mechanism 244.

Turret mechanism

20 The construction of the turret has, for the most part, already been explained. It is rotated by a vertical shaft 270 on which it is mounted and by which it is supported. The upper end of the shaft 270 is received in a tapered roller bearing 272 carried by the triangular top plate 14 of the frame. The lower end of the shaft 270 is carried in a main boss 274 depending from the plate 260 of the frame and internally supporting tapered bearings 276 and 278. The downwardly projecting end of shaft 270 carries a gear 280 and a bevel gear 282 the purposes of which will be described later.

On shaft 270 there is fixedly mounted the die plate or table 196 heretofore referred to, surrounded by the turret casting or drum 98 on which the plungers are reciprocable, which in turn is surmounted by the valve chamber casting the top of which carries the hopper. Most of the cam movements of the turret have already been explained, and it will be noted in general that the turret is a self-contained unit which need merely be rotated through shaft 270, for, upon rotation of the turret, the various cam followers associated with the valve chamber, the plunger, and the holding finger lifts are automatically operated.

The turret is rotatable on a stationary frame comprising a hollow base 132 formed by side plates bolted between a base plate 284 and a top plate 260. The hollow base carries driving mechanism, described later, and is surmounted by the three pillars 48 which carry the top plate 14 and the cam rings 46 and 68 as well as the cam cylinder 106. The base of the frame further carries the paper feed mechanism, and bag delivery mechanism next described.

Delivery system

60 The formed and filled paper bags B are delivered from the machine by a conveyor C, the bags being taken from the turret and moved to the conveyor by an intermediate delivery wheel W, these parts being best shown in Figs. 1, 2, and 11. The turret includes at its lowermost portion four wiper arms 290 indexing with the four bag forming stations of the turret. The outer end of each of these arms is provided with a wiper hand 292 which bears against the trailing edge of the bag and thus pushes the bag around with the 65 turret on an arcuate track 294 having an outer wall 296 (see Fig. 2). The wiper arms are further provided with brushes 298 which press outwardly against the inner side of the bag, thus holding the bag against the outer wall 296. The 70 primary function of brushes 298 is to prevent the

5 bags from ascending with the plunger when the plunger is elevated. By the time the formed and filled bag reaches the delivery wheel W, the plunger is, of course, elevated and the bag is being moved solely by the hand 292 and the brush 298.

The delivery wheel W consists primarily of a pair of diametrically opposed arms 300 each carrying at its outer end a hand 302. The diameter of delivery wheel W is preferably made half of the diameter of the turret, and the delivery wheel is 10 rotated at twice the rotative speed of the turret, thus giving the turret and delivery wheel equal linear speeds. To drive the delivery wheel, it is mounted upon a shaft 304 supported in a boss 306 depending from the frame plate 260. The lower 15 end of shaft 304 carries a spur gear 308 meshing with the spur gear 280 heretofore referred to. These gears are in 2 to 1 ratio, thus producing the desired equality of linear turret and delivery wheel speed.

20 Referring to Fig. 2, the delivery wheel cooperates with a semicircular track 310 provided with edge walls 312. It will be evident from an inspection of Fig. 2 that as each bag station comes to the third quadrant point, or the delivery station, one of the delivery hands 302 is moved in back of the bag and thereupon moves the same around the track 310. It should be understood that the delivery hand 302 of the delivery wheel W has its fingers staggered with respect to the 25 fingers of the hand 292 of the turret, and, while no view of the drawings brings out this feature, the point involved is clearly evident from the showing of Fig. 11, in which the hand 302 of the delivery wheel W is similarly staggered with respect to the hand 320 of the conveyor system next described.

30 The conveyor C comprises a stationary track 322 joining the semicircular track 310 of the delivery wheel. The bags B are moved along the 35 track by a series of pusher hands 320 fixedly mounted upon and spaced along a reciprocable slide 324 (see Figs. 2 and 11). This slide is reciprocable on a track 326 which is mounted upon and upwardly oscillatable with a plurality of tilting arms 328 mounted upon an oscillatable shaft 330 carried in bearings 332. Shaft 330 is oscillated by an outwardly projecting arm 334 connected to a generally horizontal tiltable lever 336 through a vertical interconnecting link 338 (see 50 Fig. 1). The lever 336 is centrally pivoted at 340, and its opposite end is provided with a cam follower 342 fitting in the cam groove of cam 1.

The end of slide 324 is connected through appropriate universal joints to a link 344 the opposite end of which is connected to the upper end of a generally upright lever 346 (see Fig. 1), said lever being pivoted at 348 and carrying at its lower end a cam follower roller 350 which fits in the face cam groove of a cam 2.

60 It will thus be evident that, upon rotation of the cams 1 and 2, the hands 320 of the conveyor C are both oscillated and reciprocated, and the timing is made such that the hands are oscillated upwardly out of the path of the bags during the 65 return reciprocation of the slide, after which the hands are tilted downwardly to a position in back of the bags, whereupon the hands are moved forwardly with the slide to urge the series of bags along the conveyor, after which the hands are 70 again tilted out of the path of the conveyor. It will further be understood that the operation of the machine is so timed that the forward movement of the hands is synchronized with the rotation of the hand of the delivery wheel W.

Drive mechanism

Referring to Fig. 1, the machine is driven by an electric motor 352 geared by chain 354 to a sprocket gear 356 which rotates the driving portion of an appropriate cone clutch. The driven part of the clutch is fast with pinion 358, so that, when the clutch is engaged, as by tilting the manual control lever 360 which rocks shaft 10 362 and thus moves the clutch yoke 364, the pinion 358 is rotated and drives gear 366. Gear 366 is used to rotate the main drive and cam shaft 368. However, instead of keying gear 366 directly upon shaft 368, I prefer to interconnect 15 these by a safety clutch 370.

This safety clutch may be of any desired type, and one example is shown in Fig. 12, referring to which it will be seen that the shaft 368 carries gear 366 freely rotatable thereon. The side 20 face of the gear hub is provided with a series of indentations 372 mating with a series of balls 374 carried in holes 376 in a flange 378 keyed at 380 to the shaft 368. The balls 374 are normally urged into recesses 372 by a reciprocable plate 25 382 which is strongly held against the balls 374 by a compression spring 384 the tension of which may be adjusted by adjusting nuts 386 threaded upon the end of the flanged sleeve 378. The pressure disc 382 is preferably keyed at 388 to 30 prevent independent rotation. It will be evident that under normal loads, the cam shaft 368 is rotated with gear 366, but upon overload, as, if a part of the machine jams, the safety clutch begins to slip, thus preventing injury to the 35 remainder of the machine.

The cam shaft 368 extends horizontally across the machine and is carried in a plurality of depending bearing pedestals 390 an end one of which is clearly shown in Fig. 12. Four of these 40 bearings are employed, creating three spaces or shaft sections therebetween, in each of which sections there are mounted two cams, numbered 1 through 6 and clearly shown in Fig. 2 of the drawings. Cams 1 and 2 are arranged back to 45 back and operate the conveyor C, cam 1 oscillating the pusher hands of the conveyor, and cam 2 reciprocating the same.

Cam 3 operates the paper feed fingers 220, the mode of operation being clearly shown in 50 Figs. 1 and 2, in which it will be noted that the generally upright operating lever 234, the upper end of which closes and reciprocates the feed fingers 220, is centrally pivoted at 392 and carries at its lower end a cam follower roller 55 394 which fits into a cam groove on the face of cam 3.

Cam 4 is employed to oscillate the knife K, and the linkage for this purpose has already been described in connection with Fig. 1, it including link 208, cam follower rod 210, and cam follower roller 214.

Cam 5 operates the paper unrolling arm 136, as is clearly shown in Fig. 3 of the drawings.

Cam 6 causes the intermittent feed of paper 65 through the paper feed roller 170. Referring to Fig. 9, it will be recollected that the desired paper feed was initiated by reciprocation of generally upright rack 176. In Fig. 1 it will be noted that this rack 176 is connected at its lower end 70 to a generally horizontal lever 400, pivoted at its inner end 402, and intermediately carrying a cam follower roller 404 which fits into a cam groove on cam 6.

The remote end of cam shaft 368 carries a gear 410 meshing with a gear 412 at the outer

end of a horizontal stud shaft 414 lying in the plane of the turret shaft 270. The inner end of the stud shaft 414 carries a bevel pinion 416 (see Figs. 1 and 2) which meshes with bevel gear 282 heretofore referred to as being secured to the lower end of the turret shaft 270. Rotation of the turret is automatically accompanied by the remaining necessary movements on the turret, as has already been explained. At the same time, through gears 280 and 308, the delivery wheel W is rotated.

Gear 412 may be additionally meshed with a gear 420 on a shaft 422 which serves no useful function in the present machine as here illustrated, but which is intended to be coupled to 15 a bag closing device. This bag closing mechanism may be of any preferred form, and is desirably of the type disclosed in a copending application of myself and Gustav Erlemann, Ser. No. 652,848, filed January 21, 1933. By driving 20 the bag closing apparatus from shaft 422, it may be operated in exact synchronism with the operation of the bag forming and filling turret.

Operation

25

The operation of the machine is best considered in terms of the four quadrants making up one complete revolution of the turret. These quadrants will be considered as beginning at the paper feed mechanism M. During the first 30 quadrant, the plunger P descends and forms a bag out of the blank of paper delivered to the die at the paper feeding station. Near the end of this quadrant the plunger valve opens, thereby initiating the filling of the bag. During the second quadrant the plunger remains in its lowered position, thereby providing ample time for the powder to be discharged and to fully empty into the bag. During the third quadrant the plunger 40 is elevated. As the plunger is elevated, the bag is held downwardly on track 294 by the brushes 298, and at the same time movement of the bag is continued by reason of the wiper hands 292 on the turret, which hands bear against the trailing edge of the bag. The bag is thus carried 45 during this third quadrant along with the turret and remains beneath the bag forming and filling station. At the same time, the plunger is being elevated. At the end of the third quadrant the outer flange or wall 296 of the turret track 294 ends, and the edge walls 312 of the delivery wheel track 310 begin. As the bag reaches the third 50 quadrant point, the hand 302 of the delivery wheel comes behind the bag and begins to move it around with the delivery wheel. At the point of junction the paths of the turret and wiper wheel are tangent and the linear speeds are equal, so that the bags are transferred smoothly and easily away from the turret. During the fourth quadrant the plunger remains in its elevated position bearing against the valve chamber, and this quadrant is used to transfer powder 55 from the measuring box into the plunger. In other words, during the fourth quadrant the cut-off valve 26 is closed and the bottom valve 56 60 is opened. Also during this quadrant the filled bag is moved by the delivery wheel W from the turret to the conveyor.

During this fourth quadrant (and, of course, during each quadrant of movement) a blank of 70 paper is prepared for the station in question which is then approaching the paper feeding point. Slack is initially provided by a quick downward and upward movement of the paper unrolling arm 136. The paper is then fed toward 75

the turret onto the skeleton table by the feed roller 170 cooperating with the pressure wheel 172. The blank of paper is next severed by downward movement of the knife, but at the same time the feed fingers 220 grip the trailing edge of the sheet of paper, which then is moved a small amount further toward the turret to position it on the skeleton table directly above the path of travel of the die. As the die comes into indexing relationship with the paper feeding station, the holding fingers are tripped and drop upon the free inner edge of the sheet of paper, and at the same time the feed fingers 220 are released, so that the blank of paper moves with the die. 10 The plunger then begins to descend, thus repeating the cycle.

During the fourth quadrant, the cut-off valve 26 is closed and the bottom valve 50 of the measuring box is opened to discharge the measured quantity of powder into the plunger, but during the remaining three quadrants the bottom valve 50 may be closed and the cut-off valve 26 opened, thereby providing more than ample time for powder to flow downwardly from the hopper and from the space immediately above the cut-off valve into the measuring box. During the rotation of the turret the powder supply in the hopper is constantly being replenished through the supply pipe 12, and the powder is agitated, sifted, and urged downwardly into the valve chambers by the stationary combs around which the hopper rotates.

It is believed that the mode of constructing and using, and the many advantages of my improved bag forming and filling machine, will be apparent from the foregoing detailed description. The machine may be operated at extremely high speeds with respect to the rate at which bags are formed and filled, and yet ample time is provided for the forming and filling of each individual bag. The powder feed is accomplished in a simple yet positive manner, and the delivery of the powder to the bag is in a straight downward path which insures full, accurate, and uninterrupted delivery. The precise measurement of the contents delivered to the bags is readily adjustable. Sticking of the powder or formation of lumps therein is obviated. Paper blanks are fed to the turret without in any way interrupting the smooth and continuous rotation of the turret. These blanks are severed from a continuous roll of paper and yet are delivered to the successive bag forming dies in exact registration therewith. The turret mechanism is so designed that simple rotation of the turret itself causes the operation of the various valves, plungers, holding fingers, and the like, by appropriate camming relationships between the rotating turret and stationary cams. The delivery system provides effective, positive, and synchronous delivery of the formed and filled bags from the turret to a conveyor along which the bags are likewise moved in synchronous relation to the operation of the entire machine. The drive of the remaining parts of the machine, exclusive of the turret, is obtained by a series of cams distributed along a single cam shaft, thus facilitating timing of the machine operations. The power drive is taken through a manual clutch and also through a safety clutch automatically operable to prevent over-load or damage to the machine. The machine may be moved manually during adjustment or starting up, by an appropriate hand wheel 430.

75 It will be apparent that while I have shown

and described my invention in preferred form, many changes and modifications may be made in the structure disclosed without departing from the spirit of the invention, defined in the following claims.

I claim:

1. A bag forming and filling machine comprising a rotatable turret, a plurality of complete bag forming and filling stations distributed around, mounted on, and rotatable with said turret, each of said stations including a die and a hollow plunger reciprocable therethrough, said die being so shaped as to fold the paper directly around the plunger to form a bag having bottom and side walls upon simple downward reciprocation of the plunger through the die, means to feed paper to the stations, means to feed filler material to the plungers, and means to deliver the formed and filled bags from the turret. 10 15

2. A bag forming and filling machine comprising a rotatable turret, means to continuously rotate the same, a plurality of bag forming and filling stations distributed around, mounted on, and rotatable with said turret, each of said stations including a die and a rectangular hollow plunger reciprocable therethrough, said die being so shaped as to fold the paper directly around the plunger to form a bag having bottom and side walls upon simple downward reciprocation of the plunger through the die, means to feed blanks of paper to the stations during rotation of the turret, means to feed a supply of powder to the open upper ends of the plungers during rotation of the turret, and means to deliver the formed and filled bags from the turret, whereby 30 35 ample time for forming and filling the bags is provided during the rotation of the turret despite the high-speed succession of bags formed by the machine.

3. A bag forming and filling machine comprising a stationary frame rotatably supporting a turret, a plurality of bag forming and filling stations distributed around said turret, each of said stations including a die, a rectangular hollow plunger vertically reciprocable therethrough, said die being so shaped as to fold the paper directly around the plunger to form a bag having bottom and side walls upon simple downward reciprocation of the plunger through the die, and a cam follower on the plunger, a stationary cylindrical 40 45 50 cam surrounding the turret and engaging the cam followers to cause reciprocation of the plungers as the turret revolves, means to feed paper to the stations, means to feed filler material to the plungers, and means to deliver the formed and filled bags from the turret. 55

4. A bag forming and filling machine comprising a continuously rotatable turret, a plurality of bag forming and filling stations distributed around, mounted on, and rotatable with said turret, each of said stations including a die and a rectangular hollow plunger reciprocable therethrough, said die being so shaped as to fold the paper directly around the plunger to form a bag having bottom and side walls upon simple downward reciprocation of the plunger through the die, means to feed blanks of paper to the stations during rotation of the turret, means to feed powder to the plungers during rotation of the turret, means to deliver the formed and filled bags from 60 65 70 75 the rotating turret, a main cam shaft and driving shaft for operating the aforesaid mechanism, a driving motor, and a safety clutch between the motor and shaft designed to slip when overloaded.

5. A bag forming and filling machine compris-

- ing a rotatable turret, a plurality of complete bag forming and filling stations distributed around, mounted on, and rotatable with said turret, each of said stations including a die and a rectangular hollow plunger reciprocable therethrough, means to feed paper to the stations, means to feed a measured supply of powder to the plungers while the plungers are elevated, each plunger having a valve and operating mechanism for temporarily retaining the charge, said valve being fully openable to provide a substantially clear hollow plunger for direct straight flow of the charge downwardly into the bag, and means to deliver the formed and filled bags from the turret.
6. A bag forming and filling machine comprising a rotatable turret, a plurality of complete bag forming and filling stations distributed around, mounted on, and rotatable with said turret, each of said stations including a die and a rectangular hollow plunger reciprocable therethrough, means to feed paper to the stations, means to feed a measured supply of powder to the open upper ends of the plungers, said means including a valve chamber above each plunger, a measuring box of adjustable volume within the chamber, a supply space above said measuring box, a cut-off valve to close the top of the measuring box, a valve closing the bottom of the measuring box but openable to drop the measured charge into the plunger, and means to deliver the formed and filled bags from the turret.
7. A bag forming and filling machine comprising a rotatable turret, a plurality of bag forming and filling stations distributed around said turret, each of said stations including a die and a rectangular hollow plunger reciprocable therethrough, means to feed paper to the stations, means to feed a measured supply of powder to the open upper ends of the plungers, said means including a valve chamber above each plunger, a measuring box of adjustable volume within the chamber, a supply space above said measuring box, a cut-off valve to close the top of the measuring box, a valve closing the bottom of the measuring box but openable to drop the measured charge into the plunger, said plunger having a valve and operating mechanism for temporarily retaining the charge, said valve being fully openable to provide a substantially clear hollow plunger for direct straight flow of the charge downwardly into the bag.
8. A bag forming and filling machine of the type comprising a rotatable turret, a plurality of complete bag forming and filling stations distributed around, mounted upon, and rotatable with said turret, each of said stations including a die and a rectangular hollow plunger reciprocable therethrough, means to feed paper to the stations, means to feed powder to the plungers, said means including an annular hopper above the plungers, means to supply powder to the hopper, means for delivering powder from the hopper to the plungers, and means to deliver the formed and filled bags from the turret.
9. A bag forming and filling machine of the type comprising a rotatable turret, a plurality of bag forming and filling stations distributed around said turret, each of said stations including a die and a rectangular hollow plunger reciprocable therethrough, means to feed paper to the stations, means to feed powder to the plungers, said means including an annular hopper above the plungers and rotatable therewith, a stationary supply pipe leading to the hopper for feeding powder thereto, means to transfer powder from the hopper to the plungers, and means to deliver the formed and filled bags from the turret.
10. A bag forming and filling machine comprising a rotatable turret, a plurality of bag forming and filling stations distributed around said turret, each of said stations including a die and a rectangular hollow plunger reciprocable therethrough, means to feed paper to the stations, means to feed powder to the plungers, said means including an annular downwardly tapering hopper above the plungers and rotatable therewith, a stationary supply pipe terminating in the hopper for feeding powder thereto, stationary means for agitating the powder in the hopper as the hopper rotates, and measuring means for delivering a measured charge of powder from the hopper to the plungers.
11. A bag forming and filling machine comprising a rotatable turret, a plurality of bag forming and filling stations distributed around said turret, each of said stations including a die and a rectangular hollow plunger reciprocable therethrough, means to feed paper to the stations, an annular hopper at the top of the turret, a stationary supply pipe leading thereto, means to feed a measured supply of powder from the hopper to the open upper ends of the plungers, said means including a valve chamber above each plunger and below the hopper, a measuring box of adjustable volume within the chamber, a cut-off valve to close the top of the measuring box, and a valve closing the bottom of the measuring box but openable to drop the measured charge into the plunger.
12. A bag forming and filling machine comprising a rotatable turret, means to rotate the same continuously without dwell, a plurality of bag forming and filling stations distributed around said turret, each of said stations including a die and a hollow plunger reciprocable therethrough, stationary paper feeding means including a skeleton table above the revolving dies of the turret, means for advancing a blank of paper on the skeleton table toward the turret, means on the turret to seize the blank of paper when the revolving die passes the paper feed means, means to feed powder to the plungers, and means to deliver the formed and filled bags from the turret.
13. A bag forming and filling machine comprising a rotatable turret, means to rotate the same continuously without dwell, a plurality of bag forming and filling stations distributed around, mounted on, and rotatable with said turret, each of said stations including a die and a hollow plunger reciprocable therethrough, said die being so shaped as to fold the paper directly around the plunger to form a bag having bottom and side walls upon simple downward reciprocation of the plunger through the die, stationary paper feeding means including a paper roll support, means for intermittently feeding a web of paper therefrom, a knife for severing a measured blank of paper, means for advancing the severed blank toward the rotating turret, means on the turret to take and hold the blank in position on the revolving die, means to feed powder to the revolving plungers, and means to deliver the formed and filled bags from the turret.
14. A bag forming and filling machine comprising a rotatable turret, means to rotate the same continuously without dwell, a plurality of bag forming and filling stations distributed around, mounted on, and rotatable with said turret, each of said stations including a die and

5 a rectangular hollow plunger reciprocable therethrough, a stationary paper feeding means alongside of the rotatable turret including a paper roll, means for intermittently feeding a web of paper therefrom onto a skeleton table above the dies, a knife for severing a measured blank of paper on the table, normally elevated holding fingers on the rotating turret, and means to drop the same upon the blank of paper to hold 10 the revolving paper on the die when the die passes the paper feeding means, means to feed powder to the plungers, and means to deliver the formed and filled bags from the turret.

15 15. A bag forming and filling machine comprising a rotatable turret, a plurality of bag forming and filling stations distributed around said turret, each of said stations including a die and a rectangular hollow plunger reciprocable therethrough, paper feeding means including a 20 paper roll, an oscillatable yieldable arm to unwind slack from the roll, means for intermittently feeding the web of paper toward the turret, a knife for severing a measured blank of paper from the web, means on the turret to hold the blank in position on the die when the die passes the paper feeding means, and means to feed powder to the plungers.

25 16. A bag forming and filling machine comprising a rotatable turret, a plurality of bag forming and filling stations distributed around said turret, each of said stations including a die and a rectangular hollow plunger reciprocable therethrough, stationary paper feeding means alongside of the rotatable turret including a paper 30 roll support, means to unwind the roll for slack, feed and pressure rollers for intermittently feeding the web of paper onto a skeleton table above the dies, a knife for severing a measured blank of paper on the table, feed fingers for advancing the severed blank on the skeleton table toward the turret, normally elevated holding fingers on the turret, and means to drop the same upon the blank of paper when the die comes into registry with the paper feed means 35 in order to hold the paper on the die, and means to feed powder to the plungers.

40 17. A bag forming and filling machine comprising a rotatable turret, means to rotate the same continuously without dwell, a plurality of bag forming and filling stations distributed around, mounted on, and rotatable with said turret, each of said stations including a die and a hollow plunger reciprocable therethrough, means to feed paper to the revolving stations, means to 45 feed filler powder to the revolving plungers, and means to deliver the formed and filled bags from the rotating turret, said means including a delivery conveyor, and means for sweeping the formed and filled bags away from the rotating turret to the delivery conveyor.

45 18. A bag forming and filling machine comprising a rotatable turret, a plurality of bag forming and filling stations distributed around said turret, each of said stations including a die and a rectangular hollow plunger reciprocable therethrough, said die being so shaped as to fold the paper directly around the plunger to form a bag having bottom and side walls upon simple downward reciprocation of the plunger through the die, means to feed paper to the stations, means to feed powder to the plungers, and means to deliver the formed and filled bags from the turret, said means including a delivery conveyor, a delivery wheel located alongside of the turret and carrying means for sweeping the formed and

5 filled bags away from the turret to the delivery conveyor, and drive means rotating both the turret and delivery wheel, the arms of the delivery wheel, the stations of the turret, and the drive means being so related as to provide for synchronization and equal linear speed of operation therebetween.

10 19. A bag forming and filling machine comprising a rotatable turret, means to rotate the same continuously without dwell, four bag forming and filling stations distributed around said turret, each of said stations including a die and a rectangular hollow plunger reciprocable therethrough, stationary means alongside of the rotatable turret to feed blanks of paper to the stations during rotation of the turret, means to feed a supply of powder to the open upper ends of the plungers during rotation of the turret, and means to deliver the formed and filled bags from the turret, said means including a delivery 15 conveyor, a small delivery wheel located alongside of the turret ahead of the paper feed means and carrying two arms for sweeping the formed and filled bags away from the rotating turret to the delivery conveyor, and means gearing the wheel and the turret in two to one turning ratio.

20 20. A bag forming and filling machine comprising a die, a hollow plunger reciprocable through said die means to supply a charge of powder to the plunger, a valve near the bottom 25 of the plunger to temporarily retain said charge, and means to so fully open said valve that the plunger is substantially fully cleared for direct straight downward flow of the charge.

25 21. A bag forming and filling machine comprising a die, a rectangular hollow plunger reciprocable through said die, means to supply a measured charge of powder to the open upper end of the plunger, a valve near the bottom of the plunger to retain said charge until the bag 30 is formed, means including linkage within the plunger for opening the valve near the end of the stroke of the plunger, said linkage being so disposed closely adjacent one wall of the plunger and said valve being so fully openable that the 35 plunger is substantially fully cleared for direct straight downward flow of the charge when the valve is opened.

35 22. A bag forming and filling machine comprising a dye, a rectangular hollow plunger reciprocable through said die, means to supply a measured charge of powder to the open upper end 40 of the plunger, said means including a valve chamber carrying an adjustable measuring box, a cut-off valve at the top of the measuring box, 45 a valve normally closing the lower end of the measuring box but openable to drop the measured charge of powder into the upper end of the plunger, and a valve near the bottom of the plunger to retain said charge until the bag is 50 formed.

55 23. A bag forming and filling machine comprising a die, a rectangular hollow plunger reciprocable through said die, means to supply a measured charge of powder to the open upper end 55 of the plunger, said means including a valve chamber intermediately carrying a measuring box having a movable side, micrometer screw adjustment means for moving the side and thereby varying the volume of the measuring box, a cut-off valve slidable across the open top of the measuring box, a valve normally closing the lower end of the measuring box but openable to drop the measured charge of powder into the upper 60 end of the plunger, and a valve near the bottom 65

of the plunger to retain said charge until the bag is formed.

24. A bag forming and filling machine comprising a die, a rectangular hollow plunger reciprocable through said die, means to supply a measured charge of powder to the open upper end of the plunger, said means including a valve chamber carrying a measuring box, a cut-off valve at the top of the measuring box, a valve 10 normally closing the lower end of the measuring box but openable to drop the measured charge of powder into the upper end of the plunger, a valve near the bottom of the plunger to retain said charge until the bag is formed, and means to 15 so fully open said valve that the plunger is substantially fully cleared for direct straight downward flow of the charge.

25. A bag forming and filling machine comprising a die, a rectangular hollow plunger reciprocable through said die, means to supply a measured charge of powder to the open upper end of the plunger, said means including a valve chamber intermediately carrying a measuring box having a movable side, micrometer screw 20 adjustment means for moving the side and thereby varying the volume of the measuring box, a cut-off valve slideable across the top of the measuring box, a valve normally closing the lower end of the measuring box but openable to drop 25

the measured charge of powder into the upper end of the plunger, a valve near the bottom of the plunger to retain said charge until the bag is formed, means including linkage within the plunger for opening the valve near the end of the stroke of the plunger, said linkage being so disposed closely adjacent one wall of the plunger and said valve being so fully openable that the plunger is substantially fully cleared for direct straight downward flow of the charge when the 10 valve is opened.

26. A bag forming and filling machine comprising a rotatable turret, a plurality of bag forming and filling stations distributed around said turret, each of said stations including a die 15 and a hollow plunger reciprocable therethrough, means to feed paper to the stations, and means to feed a measured supply of powder to the plungers, said means including a valve chamber on the turret above each plunger, a measuring 20 box within the chamber, a cut-off valve to close the top of the measuring box, a valve closing the bottom of the measuring box but openable to feed the measured charge into the plunger, cam followers for operating said valves, and sta- 25 tionary annular cams surrounding the turret for actuating said cam followers as the turret revolves.

THEODORE SCHILDER.
